UNITED STATES PATENT OFFICE.

CHARLES A. RIGHTER, OF PHILADELPHIA, PENNSYLVANIA, ASSIGNOR TO
JAS. AND GEO. D. BROMLEY, OF SAME PLACE.

DESIGN FOR A CARPET.

SPECIFICATION forming part of Design No. 14,277, dated September 11, 1883.
Application filed July 27, 1883. Term of patent 3½ years.

To all whom it may concern:

Be it known that I, CHARLES A. RIGHTER, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim—
The design for carpets, as herein shown and described.

CHARLES A. RIGHTER.

Witnesses:

BENJN. VAIL,
HARRY HARDWICK.
